UNITED STATES PATENT OFFICE.

CARL E. ANDERSON, OF BROOKLYN, NEW YORK, ASSIGNOR TO AMERICAN MACHINE AND FOUNDRY COMPANY, A CORPORATION OF NEW JERSEY.

STRAINING PRIMER FOR PUMPS.

Application filed August 30, 1924. Serial No. 735,067.

This invention relates to an improved straining primer or combined strainer and primer for pumps, its main object being the production of a device of this character which is simple, compact, inexpensive, easily cleaned, and highly efficient for removing foreign matter from the liquid pumped. With this and other objects not specifically mentioned in view, the invention consists in certain constructions and combinations which will be hereinafter fully described and then specifically set forth in the claims hereunto appended.

In the accompanying drawings which form a part of this specification and in which like characters of reference indicate the same or like parts, Fig. 1 is a sectional elevation of a device constructed in accordance with the invention, and Fig. 2 is an inverted plan view taken on the line 2--2 in Fig. 1.

In carrying the invention into effect, there is provided a casing having intake and outlet ports near its top in order to retain a body of liquid within the casing at all times for pump priming purposes, said casing being adapted to be connected in the suction pipe line adjacent a pump. This casing is further provided with an apertured wall dividing its interior into an intake chamber in communication with said intake port and an outlet chamber in communication with said outlet port, and a straining device is located in the path of liquid flow from said intake chamber through said apertured wall to said outlet chamber and thence through said outlet port. These parts may be varied in construction within the scope of the claims, for the particular device selected to illustrate the invention is but one of numerous possible concrete embodiments of the invention. The invention, therefore, is not to be restricted to the precise details of the structure shown and described.

Referring to the drawings, 3 indicates a casing which is provided with a cover 4 normally closing the top of said casing. The casing 3 has an intake port 5 and an outlet port 6, both being located near its top and diametrically opposite each other. The intake port 5 is in communication with an intake chamber 7, and the outlet port 6 is in communication with an outlet chamber 8, the latter extending across the bottom of the

chamber 7 and up one of its sides. The 55 casing is provided with an apertured wall dividing its interior into these two chambers, and this wall is apertured at 9, at the bottom of the chamber 7.

The flow of the liquid when the device is 60 in operation is through the intake port 5 to the chamber 7, thence through the apertured wall at 9 to the chamber 8, and thence out through the outlet port 6. To arrest foreign matter carried into the device by the flowing 65 liquid, there is provided a strainer in the path of the flowing liquid from the intake chamber through the apertured wall to the outlet chamber, and as shown this strainer is cylindrical in form as at 10 and is inter- 70 posed between the bottom of the intake chamber 7 and the cover 4. It is of a diameter approximately the same as the diameter of the aperture at 9 of the dividing wall in the casing.

For the purpose of collecting foreign matter separated from the flowing liquid passing through the strainer 10, there is provided an annular receptacle for said matter which is marked 11 and which is secured to 80 the strainer 10 so that upon removal of the cover 4 the strainer and receptacle may be removed from the casing together for cleaning purposes.

It will be noted that although the device 85 is compact the effective area of the strainer is very large with respect to the area of the intake and outlet ports. It therefore offers but slight resistance to the action of the pump. Moreover, it will need cleaning only 90 at infrequent intervals unless the liquid pumped is exceptionally dirty. It will also be noted that since the device is always full of liquid to the level of the intake and outlet ports, this liquid is always available for 95 priming purposes. In other words, water is entrapped in the intake and outlet chambers if, by reason of pump stoppage, the water in the pipe line connected with the intake port 5 runs back to the source of supply. When the pump is again started, it first acts upon this entrapped water which primes and seals it so that it will suck the air from the pipe line connected with the intake port 5, followed of course by the water 100 flowing into said pipe line when a partial vacuum is set up therein.

For the purpose of permitting drainage

of the outlet chamber if desired, there is provided a threaded plug 12 in the bottom of the casing 3.

When the device is in operation, the liquid 5 being pumped flows through the intake port 5 to the annular space surrounding the strainer 10, thence through said strainer, thence through the aperture 9 of the dividing wall into the outlet chamber 8 and 10 up its vertical part to and through the outlet port 6, any foreign matter contained in the liquid being arrested by the strainer and 15 permitted to fall into the receptacle 11 surrounding the strainer.

15 What is claimed is:

1. A straining primer for pumps comprising a casing having intake and outlet ports near its top and provided with an apertured wall dividing its interior into an intake 20 chamber in communication with said intake port and an outlet chamber in communication with said outlet port, a removable cylindrical strainer interposed between the top and bottom of said intake chamber in the

25 path of liquid flow from said intake chamber through said apertured wall to said outlet chamber, and an annular receptacle for foreign matter surrounding and secured to and removable with said strainer.

2. A straining primer for pumps comprising 30 a casing having intake and outlet ports near its top and provided with an apertured wall dividing its interior into an intake chamber in communication with said intake port and an outlet chamber in communication with said outlet port, a cover normally closing the top of said casing, a cylindrical strainer interposed between said cover and the bottom of said intake chamber in the 35 path of liquid flow from said intake chamber through said apertured wall to said outlet chamber, and an annular receptacle for foreign matter surrounding and secured to said strainer and removable with said strainer when said cover is removed.

40 In testimony whereof, I have signed my name to this specification.

45 CARL E. ANDERSON.
